(57) **CLAIM**

The ornamental design for a bottle, as shown and described.

DESCRIPTION

FIG. 1 is a front perspective view of a bottle according to the present invention.

FIG. 2 is a front view of the bottle according to FIG. 1, with the rear being identical.

FIG. 3 is a corner view of the bottle according to FIG. 1, with the other three corners being identical.

FIG. 4 is a top view of the bottle according to FIG. 1; and, FIG. 5 is a bottom view of the bottle according to FIG. 1. The broken lines in the drawings depict portions of the bottle that form no part of the claimed design.

1 Claim, 4 Drawing Sheets
